UNITED STATES PATENT OFFICE.

JOHN G. HEIVNER, OF ORLAND, CALIFORNIA.

ANIMAL-CONTROL DEVICE.

1,251,519.

Specification of Letters Patent. Patented Jan. 1, 1918.

Application filed February 20, 1917. Serial No. 149,794.

To all whom it may concern:

Be it known that I, JOHN G. HEIVNER, a citizen of the United States, residing at Orland, in the county of Glenn and State of California, have invented a new and useful Animal-Control Device, of which the following is a specification.

The object of my invention is to provide a safe and reliable means for checking and controlling fractious, or unruly horses, or other animals by means of a specially contrived arrangement applied to the head of the animal.

With these objects in view the invention consists in the arrangement and combination of parts which will be hereafter fully described, shown in the accompanying drawings, and pointed out in the claims.

In the drawings Figure 1 is a side view of the contrivance attached to a horse. Fig. 2 is a side view, on an enlarged scale, of the tightening-strap used. Fig. 3 is a side view, on enlarged scale, of a modification of the guiding reins when used with a spring bit.

Fig. 4 is a side view, partly in section, of a form of spring bit to be used with the modification of the guiding reins. Like numerals designate the same parts in the different figures.

An ordinary bridle is used. A tightening-strap 2 is loosely wound twice around the nose and jaw of the animal, above the mouth bit, over and under the part 17 of the bridle and joined under the jaw, as shown more clearly in Fig. 2, at which place is attached a ring 5. Secured to the tightening-strap is a ring 3, there being a like ring on the opposite side of the animal's jaw but not shown in the figures. The guiding rein 10 is attached to the tightening ring 3 and the bit ring 4, it being divided for that purpose at 13, the part 7 being elastically yieldable and the part 8 non-yieldable. It is understood that there is also a rein on the opposite side

of the animal similarly constructed and attached. Either a plain or spring bit can be used in connection with the reins. With a plain bit that part of the rein attached to the bit ring 4 is formed with a spring 7, which is omitted with a spring bit, being then a continuous strap as shown in Fig. 3. The martingale 6 is attached to the tightening ring 5, at one end, and at the other to the surcingle 20 at 12 and is adjustable by means of the buckle 18. To the martingale are secured two rings 15 and 19 so placed

that a connecting spring 16 will give a slack section above it to the martingale. Attached to the throat strap 23 of the bridle is a ring 11. Between it and a loose ring 14, on the slack part of the martingale, is placed a spring 9 which completes the working arrangements of the device. It is understood that all the parts are to be so adjusted as to have a proper relation to each other in their operation.

Fig. 4 shows a form of spring bit which can be used, if preferred, to a plain bit. It is formed of a curved, tube bar 21 containing a spring 22 fastened at the ends of which are bit rings 4, 4, tension on which, on the inner side of the curve, causes the spring to elongate. With this bit the spring 7 is omitted from the rein, the construction being that shown in Fig. 3. The purpose of the springs is to give a gentle, elastically yieldable connection of the parts in their operation and to insure their return to normal positions after the strains have been released from them.

The operation of the device is as follows: When the rein is unrestrained it droops sufficiently so that the part 8 will be slack. Tension on the rein is carried first yieldingly by means of the spring 7 to the mouth bit, 85 a gentle strain being ordinarily sufficient for guiding the animal; but a continued and stronger tension extends the spring sufficiently for the part 8 of the rein to become taut and carry the strain firmly to the tightening-strap 2 through the ring 3. The tightening-strap being loosely wound twice around the nose and jaw of the animal, and is thus left free to slip, the strain on it causing it to tighten and close tightly the animal's jaw, which has the effect of subduing the animal. When an animal is affrighted it invariably raises its head. So that the control will be effective, automatically, without using the reins is the purpose of the construction of the martingale shown and the connecting spring 9 which draws on the slack part of the martingale through the throat strap. As the animal's head is raised the strain is first received gently by means 100 of the springs but further upward movement of the head causes the springs to extend until the martingale is taut, the slack section above the spring 16 straightening out, and the tension on the tightening-strap becomes intense 110 and clamps the animal's jaw, the same effect being obtained as when the reins are used,

and the animal learns in time to become less restive because it will instinctively know that following the gentler warning given through the springs will come the drastic 5 action of the tightening-strap, which it will fear, and it will become gentle.

The tightening-strap will also be effective, without the use of reins, by means of the lead strap 1, pulling on which will draw directly 10 on the tightening-strap, through the ring 5, and cause it to slip and clamp the animal's jaw the same as tension on the martingale direct.

Having thus described my invention what 15 I claim as new and desire to secure by Letters Patent, is—

1. In an animal control device the combination of a tightening-strap loosely applied around the nose and jaw of the animal with 20 a martingale having both an elastically yielding and a non-yieldable connection with the tightening-strap, the elastically yielding connection being arranged to be first operated and the non-yieldable connection 25 to be subsequently operated, for the purposes set forth.

2. In an animal control device the combination of a bridle, of a tightening-strap loosely applied around the nose and jaw of the animal, of a throat strap of the bridle, 30 and of a martingale having a combined elastically yieldable and a non-yieldable connection with the tightening-strap, and an elastically yieldable connection with the throat strap.

3. In an animal control device the combination of a bridle, a mouth bit, a throat strap of the bridle, a tightening-strap applied around the nose and jaw of the animal, 40 a martingale having a combined elastically yieldable and a non-yieldable connection with the tightening-strap, and an elastically yieldable connection with the throat strap, and of guiding and controlling reins having an elastically yieldable connection with the 45 mouth bit and a non-yieldable connection with the tightening-strap, substantially as shown and described.

JOHN G. HEIVNER.
